United States Patent Office.

CHARLES EDWARD BOMAN, OF SAN FRANCISCO, CALIFORNIA.

Letters Patent No. 91,706, dated June 22, 1869.

IMPROVED STEP-LADDER

The Schedule referred to in these Letters Patent and making part of the same.

To all whom it may concern:

Be it known that I, CHARLES EDWARD BOMAN, of San Francisco, in the county of San Francisco, and State of California, have invented certain new and useful Improvements in Step-Ladders; and I do hereby declare that the following is a full and exact description of the same, reference being had to the accompanying drawings, and to the letters of reference marked thereon.

The nature of my invention is to provide a step-ladder so constructed that it can be easily and safely ascended, and, at the same time, when the top step is reached, the person mounting will not be thrown down by the toppling of the ladder.

In constructing step-ladders, the necessity of having the frame-work as light as possible is apparent, as well as to form the base so as to occupy as little room as possible, when placing it in angles and corners; but, in such a construction, the danger of falling in ascending, by reason of the swaying to and fro, as well as the tipping of the ladder, when the apex or top is reached, is very great.

To overcome these objections, and, at the same time, provide a light implement, I employ a rail, which is hinged to the side of the ladder by jointed arms, so that it can be folded down when not in use.

From a cross-bar, near the base of the flap or brace, extends a jointed bar, with a notch in the end, which reaches to a step beneath, where a catch is placed, and in which the end of the bar enters, where a spring prevents it from rising or flying out, if a sudden swaying of the ladder takes place.

Referring to the drawings—

Figure 1 is a side view of my implement folded up.

Figure 2 is a front view, also folded up.

Figure 3 is a side view, with the ladder in position, and side-rail broken away, to show the extension-bar and its attachments.

A is the support or flap, which is hinged to the ladder proper in the usual way.

To this support, a little below the centre, is affixed a cross-piece, b, to which is attached an arm or bar, c, jointed at c'.

The end of the bar is provided with a notch, d, which, when the support is extended, sits in the catch e, that is attached to the under side of the step f, in which position the bar is held by a small spring, g, so that it will not be liable to become disengaged, and allow the ladder to fall.

The bar is also useful for binding the steps and support together, as, in closing up, the bar slides along through the catch, until past the joint, when it is folded over against the front of the steps, where it is held by a hook, h, entering a hole, i.

As a support when ascending and descending, as well as when standing on the top step, I attach, to one or both sides of the ladder, a rail, j, by means of arms k, which are bolted to the side-rail, and admit of being turned up and down.

The arms are also provided with joints, l, so that the rail can be folded down when not in use.

When the rail is extended or raised, it is kept in position by a spring, m, that is attached to the side-rail of the ladder.

My improved ladder will be found of great usefulness in gathering fruit from trees and vines, as well as for use in buildings where great height is to be attained.

Having thus described my invention,

What I claim, and desire to secure by Letters Patent, is—

The bar c, having the joint c', when used in connection with the catch e, and spring g, and the hook h, in manner described, for the purpose set forth.

In witness whereof, I have hereunto set my hand and seal.

CHARLES EDWARD BOMAN. [L. S.]
